UNITED STATES PATENT OFFICE

VERGIL MULHOLLAND, OF WEST HARTFORD, CONNECTICUT, ASSIGNOR TO HARTFORD-EMPIRE COMPANY, OF HARTFORD, CONNECTICUT, A CORPORATION OF DELAWARE

LEER

Application filed December 27, 1927. Serial No. 242,877.

This invention relates to leers for glassware, and more particularly to leers of the type used for baking or fusing a vitreous enamel or other decoration on the ware and subsequently annealing it, although the leer as shown and hereinafter described and also various individual features disclosed hereby and claimed herein may be useful in the usual annealing of glass where no decorating is to be done.

The process of fusing or baking an enamel decoration on glassware includes first the gradual heating of the ware to a point at which the enamel or flux used therewith will fuse, then the maintenance of this temperature for the time necessary for the fusion or maturing of the color, and finally the annealing of the ware, that is, the cooling of it from this high fusion temperature slowly enough to prevent the introduction of permanent strains to the "lower annealing temperature," which is that at which the glass is substantially set and below which no permanent strains will be introduced into the ware. From this point the ware may be cooled quite rapidly to a temperature at which it may be safely handled for packing or other purposes.

The usual annealing leers as now constructed have provision for only the annealing and cooling steps of the above process, and one of the objects of the present invention is, therefore, to provide a leer having provision for the gradual heating and the maintained heat steps of the process in addition to and in line with the usual annealing and cooling steps, whereby the entire process may be carried on continuously in a substantially unitary device.

In carrying out the second or maintained temperature step of the process, a fairly high heat is used and at the same time it is necessary to have close control of the heat; and for this purpose I preferably employ a special type of fire box located in a novel manner with respect to a leer tunnel. The provision of this special fire box and its location with respect to the tunnel are further objects of the invention.

In handling certain types of decorated

adjacent to the top and the ware is of relatively light weight, difficulty is sometimes experienced in the ware deforming at the bottom during the time of maintained high temperature, as both temperature and time factors are necessary in the proper maturing of the decoration.

Another object of this invention is, therefore, to provide a leer in which the top may be heated to a greater degree than the bottom for the required time, whereby to mature the decoration at the top while the bottom is maintained cool enough to prevent its deformation, provision later being made for annealing the entire article to remove any strains which may have been introduced by such differential heating. If the shape of the ware makes it advisable, however, the bottom may be maintained hotter than the top.

Another object of the invention is to provide for a control of the temperature gradient in the leer by a variation in the amount or velocity of the heating media, while maintaining its initial or entering temperature substantially constant.

A further object of the invention is to enable the maintenance of a substantially constant rate of cooling of the ware by the admission of proper amounts of air into the heating flues, by so proportioning the size and spacing of the air inlets that substantially the same damper setting at each inlet will give the desired result, thus permitting the proper operation of the leer by comparatively unskilled labor.

Other objects and advantages of my invention will appear from the following specification and subjoined claims when taken in connection with the accompanying drawings, in which:

Figure 1 is a diagrammatic vertical longitudinal sectional view of the forward half of a leer embodying my invention;

Fig. 2 is a similar view of the rear half of the leer shown in Fig. 1;

Fig. 3 is a section taken substantially on the line 3-3 in Fig. 1;

Fig. 4 is a section taken substantially on the broken line 4-4 in Fig. 1;

Fig. 5 is a section taken substantially on the broken line 5—5 in Fig. 2;

Fig. 6 is a section taken substantially on the line 6—6 in Fig. 2.

5 Fig. 7 is an elevation of one of the damper members for admitting atmospheric air to the lower flues having relatively small openings for air admission;

10 Fig. 8 is an elevation of a damper member having larger openings; and

Fig. 9 is a section on the line 9—9 of Figs. 7 and 8 showing the configuration of the damper members.

Referring to the drawings, the leer tunnel 15 may be constructed of a plurality of substantially interchangeable sections 2 arranged in end to end relation and suitably supported in any desired manner, as for example, the manner shown in my prior Patent 1,560,481, granted Nov. 3, 1925. The ware may be carried through the leer in any suitable manner, as for example, upon a flexible wire belt 3 which may be driven by suitable mechanism (not shown), this 20 mechanism preferably being of the type shown in my prior patent above referred to. Heating flues 4 and 5 extend longitudinally beneath the forward and rear portions of the tunnel respectively and communicate 25 through a passageway 6 with a common fire box 7 disposed beneath the leer at a point spaced from the entrance end of the tunnel. The damper 8 controls the passage of the heating media through the flue 4 from the 30 fire box 7, and the damper 9 the passage of the heating media through flue 5, thus providing for independent regulation of the drafts in these flues. The fire box 7 may be provided with one or more suitable burners 35 10 for oil, gas or other fuel which may be directed thereinto through the opening 11, air to support combustion entering the fire box through the annular space between the burner 10 and the sides of the opening 11. 40 A desired amount of diluting air may be admitted to the fire box 7 through the passage 12, this amount being controlled by a suitable damper 13. By suitable regulation 45 of the burner 10 and the dampers 13, 8 and 9, the temperature and volume of the heating gases passing along the flues 4 and 5 respectively, may be controlled. It is usually 50 desirable to control the temperature of the gases passing from the fire box into flues 55 through the passage 6 within narrow limits, and by suitable control of the amounts and 60 velocity of gases passing along the flues 4 and 5, the temperature drop along these flues may be varied at will, as the heat loss through 65 the insulation 14 from the flue 4, and the forward portion of the flue 5, will not vary materially with a change in the velocity of the gases passing therethrough. The flue 4 is provided with an outlet passage 15 adjacent to the receiving end of the tunnel,

which passage communicates with passages 16, one on each side of the tunnel, leading to header 17, which in turn communicates through the ducts 18 and 19 with the suction device 20, here shown as a motor driven fan. 70

In order to control the temperature gradient in the tunnel 2 by cooling the gases in the flue 5, I provide a plurality of dampered air inlet passages 21 which are spaced apart unequal distances, as seen in 75 Fig. 2, the distances being progressively less toward the discharge end of the leer. Instead of this progressive change in the spacing of the passages, or in addition thereto, 80

the effective area of these passages 21 may be progressively greater toward the discharge end of the leer, whereby with a given damper setting, that is, with the dampers in all of the passages 21 opened at a certain given angle, increasing amounts of cooling 85 air will be admitted per unit length of the tunnel. In practice a convenient way of accomplishing this variation using similar parts for economy in manufacture is to provide damper members with progressively 90

greater openings, but all cooperable with 95 ports of the same size. I prefer to construct the dampers from cylindrical bars and having cut out segments to permit the passage of air when the bars are rotated to the proper 100 positions. Such bars are shown in Figs. 7, 8 and 9 at 21^a and 21^b respectively and are provided with cut out segments 21' of varying length so that the bar 21^a may, for example, be provided with four cut out portions or segments each of two inches length thus providing an aggregate length of eight 105 inches, while the bar 21^b may be provided with two cut out segments each of fifteen inches, or an aggregate length of thirty 110 inches. I plan to use bars having progressively increasing total or aggregate cut out 115 lengths or openings toward the exit end of the leer for accomplishing the aforesaid objects. The reason for this is that it requires less cooling air to cool the gases a given number of degrees at a point where they are hotter and their total volume is less than where they are cooler, and the size and 120 position of these inlets is such that with the dampers set at a certain angle, the temperature drop per unit length of tunnel will be constant, so that the rate of cooling of the ware in the tunnel will be substantially constant. This is an important feature, as 125 leers of this character are usually operated by relatively unskilled labor, and in order to have proper operation with dampers and passages of uniform size and spacing, different damper settings would be required which would require the services of a skilled operator.

The flue 5 communicates through an inclined passage 22 with a header 23, communicating in turn with passages 24, one on each 130

side of the tunnel 1, which lead to a top header or wind box 25 communicating with the fan 20. Thus it will be seen that flues 4 and 5 are at all times maintained at sub-atmospheric pressure, whereby any leaks in these flues, as for example, in the joints between contiguous sections 2, will not permit the combustion products to impinge upon the ware or cause hot spots in the tunnel, but will 10 only serve to withdraw slight amounts of air from the tunnel which has no harmful effect.

The portion 26 formed as a prolongation of the flue 5 to the right of the inclined passage 22 is used to accelerate the cooling of the ware 15 and is provided with a dampered air inlet passage 27 adjacent to the discharge end of the leer, cold air from the atmosphere flowing through the passage 27 and to the passage 22 counter-current to the direction of 20 motion of the ware.

Flues 28 and 29 extend longitudinally above the tunnel 1 and preferably have a common wall with the roof of said tunnel in the same manner that flues 4 and 5 have a 25 common wall with the floor of the tunnel. A specially designed fire box 30 is interposed between the flues 28 and 29 and has a common wall 31 with the top of the tunnel. Fire box 30 is provided with a plurality of burners 31 30 symmetrically disposed with respect thereto, preferably three on each side, these burners being directed into openings 32, similar to the opening 11 in fire box 7 and having annular spaces as described above to provide for the 35 entrance of primary air to support combustion. Openings 33 controlled by dampers 34 are provided, preferably one for each of the burners 31 for the purpose of admitting controllable amounts of secondary and diluting 40 air, the control being similar to that described above in connection with the lower fire box 7.

The flue 28 is provided with one or more outlet openings 35, two being shown, which are controlled by suitable dampers 36 and 45 which communicate through header 17 and conduits 18 and 19 with the fan 20.

Flue 29 may be provided with a plurality of dampered air inlet openings 37, two of which are shown, for the same purpose described above in connection with air inlet 50 openings 21. This flue is separated by a suitable dividing wall 38 from a cooling flue 39, to be described. The heating media are drawn off from the flue 29 by one or more 55 suitable passages 40 controlled by dampers 41, the passages 40 communicating through the conduit 19 with the suction fan 20. Thus it will be seen that the draft through flues 28 and 29 is controlled respectively by 60 dampers 36 and 41 in a manner similar to that in which the draft through flues 4 and 5 is controlled by dampers 8 and 9 respectively.

The flue 39 is formed as a prolongation of the flue 29 at the cooler end portion of the leer for accelerating the cooling of the ware,

and is open to the atmosphere at the exit end of the leer as shown at 42. The flue 39 communicates with the conduit 19 through a plurality of spaced dampered air outlet passages 43 by which the amount of cooling air 70 drawn in a direction counter-current to that of the movement of the ware through the flue 29, and the distance which it passes may be controlled.

When used as a decorating leer, the glass-ware entering the left hand end, as seen in Fig. 1, is at substantially room temperature and is heated at a safe rate by transmitted and radiated heat, and to a lesser extent by convection currents, from the flues 4 and 28 75 in which the gases flow in a direction counter-current to the ware, so that by the time the ware reaches a point substantially above the passageway 6, it has been brought almost to the fusing temperature of the decorating 80 material or the flux used therewith. In the next zone to the front edge of the fire box 30, the ware will be maintained at a substantially constant temperature, due to the fact that the gases in the flues 5 and 28 are traveling in opposite directions, and thus each tends to balance the temperature drop in the other. In the next zone, that is, immediately under the furnace 30, which is of substantial longitudinal extent and which is of substantially the 85 same width as the tunnel, the ware will be maintained again at a substantially constant temperature which may be maintained 90 slightly higher than the temperature in the preceding zone. During the passage through 95 these two zones, the fusion of the decorating material onto the ware takes place. It is necessary to provide a material time for this fusion to take place as well as a certain temperature, so that the offset position of fire 100 boxes 7 and 30 and the longitudinal extent of fire box 30 are both of prime importance. The heating effect on the ware by fire box 30 is still further augmented by the fact that this fire box has a common wall with the roof of 105 the tunnel for substantially its entire length and breadth, and the burners 31 therein are symmetrically disposed with respect to the fire box, so that a constant temperature may be maintained.

In fusing the decoration on certain types of ware, namely that type in which the decoration is all adjacent to the top of the articles and in which the articles are relatively light, it is sometimes desirable to heat the 110 top decorated portion hotter than the bottom, so as to mature the decoration without the possibility of heating the bottom portion to an extent likely to cause deformation thereof. The particular type of fire box 30 115 and its individual control, apart from that of the fire box 7, is especially adapted for 120 this purpose.

After the color has been matured on the ware, either with or without differential

heating as described above, it must be annealed to take out any strains which may have been introduced and to prevent the introduction of new strains, and for this purpose a material length or zone in the tunnel is provided, namely that shown in Fig. 1 to the right of the fire box 30, in which zone there are no passages to the flues 5 and 29 for the entrance of cooling air, but the temperature is regulated by the velocity control described above and by the decreasing thickness of the insulation 14. The succeeding zone of the tunnel which may be said to be that portion shown at the left in Fig. 2 to a point near the partition 38 between the flues 29 and 39, constitutes a retarded cooling zone in which the ware is slowly cooled to approximately the "lower annealing temperature" described in the introduction. During its passage from a position under the fire box 30 to approximately the end of this last mentioned zone, the normal rate of cooling of the ware is retarded to permit the permanent strains to work themselves out of the ware 25 and to permit it to be cooled to a point below which they will not be reintroduced. The cooling below this temperature may be carried on at a relatively rapid rate. The annealing and cooling portions of the leer to 30 the right, as seen in Figs. 1 and 2 of the fire box 30, are preferably regulated so that all portions of the leer in any transverse section will be maintained at a substantially constant temperature, thus tending to remove 35 any strains which have been previously introduced by differential heating or in any other manner. This accelerated cooling takes place in the succeeding zones, too rapid cooling being prevented in the first part of 40 these zones by carrying the lower flue 5 to a point nearer the discharge end of the leer than the upper heating flue 29 and depending upon hot convection currents rising from the hot lower flue and cool currents falling from 45 the cooler upper flue 39 to govern the rate of cooling of the ware. The final cooling immediately adjacent to the discharge end of the tunnel may be further accelerated by providing the counter-current cold air flue 26 50 in addition to the cooling effect of the top flues 39.

The leer tunnel used for decorating purposes may well be longer than in the ordinary annealing leer, such as is shown in my prior patent above referred to, so as to provide the necessary space and time for heating the ware from room temperature to the fusion temperature of the decorating material and for maintaining it at the high fusion temperature before the annealing is started.

It should be noted that the top flues 28, 29 and 39 are all connected with the single suction device 20 and are maintained at sub-atmospheric pressure for the reasons de-

scribed above in connection with the lower flues 4 and 5.

While I have shown and described but one embodiment of my invention, it is to be understood that many changes might be made therein, and many of the details herein shown and described might be used in other connections, and I do not wish, therefore, to be limited except by the scope of the appended claims, which are to be construed as broadly as the prior art permits. 75

I claim as my invention:

1. A leer comprising an elongate leer tunnel, means for conveying articles of glassware therethrough, a plurality of heating flues associated with different walls of said tunnel, means to supply heating media thereto at points spaced from the ware-receiving end of the leer, whereby to provide an initial progressively hotter zone, a zone of maintained heat, and a retarded cooling zone, and a plurality of cooling flues to provide a final accelerated cooling zone along the path of the ware through said tunnel. 80

2. A decorating and annealing leer comprising an elongate leer tunnel, means for conveying articles of glassware therethrough, a plurality of heating flues associated with said tunnel, means to supply regulable amounts of heating media thereto at points spaced from the ware-receiving end of the leer, whereby to provide an initial progressively hotter zone to bring the ware up to the desired temperature while passing the media in a direction counter-current to the movement of the ware, a zone of maintained substantially constant temperature controllable by the velocity of the media, and a zone of progressively decreasing temperature during which the normal rate of cooling of the ware is retarded while the media pass through said flues in the direction of movement of the ware, and a plurality of longitudinally extending cooling flues in prolongation of said heating flues and adapted to conduct regulable quantities of atmospheric air in a direction counter-current to the movement of the ware to provide a zone in which the normal rate of cooling of the ware is accelerated, the leer being materially longer than the usual annealing leers to provide an initial heating zone for the ware. 95

3. A leer comprising an elongate tunnel, means for moving articles of glassware therethrough, a longitudinal heating flue above said tunnel, means for supplying heating media to said flue intermediate its ends, and means for conducting the media from said flue adjacent to both ends. 100

4. A leer comprising an elongate tunnel, means for moving articles of glassware therethrough, a longitudinal heating flue above said tunnel, means for supplying heating media to said flue intermediate its ends, whereby to provide an initial progressively 115

hotter zone and a progressively cooler zone, a cooling flue formed as a prolongation of said heating flue at the exit end portion of said tunnel and adapted to conduct cooling media in a direction counter-current to the ware, and means communicating with the ends of said flues for conducting the various media therefrom.

5. A leer comprising an elongate tunnel, 10 means for moving articles of glassware there-through, a longitudinal heating flue beneath said tunnel, a second longitudinal heating flue above said tunnel, means for supplying heating media to said flues intermediate their 15 ends, and means for withdrawing the media from said flues adjacent to their ends to maintain them at subatmospheric pressure.

6. A leer comprising an elongate tunnel, 20 means for moving articles of glassware there-through, a longitudinal heating flue beneath said tunnel, a second longitudinal heating flue above said tunnel, means for supplying heating media to said flues intermediate their 25 ends, whereby to provide an initially progressively hotter zone and a progressively cooler zone, cooling flues formed as prolongations of said heating flues at the exit end portion of the tunnel and adapted to conduct cooling media counter-current to the ware, and means 30 adjacent to the ends of said flues for withdrawing the various media therefrom to maintain them at subatmospheric pressure.

7. A leer comprising an elongate tunnel, 35 means for moving articles of glassware there-through, a longitudinal heating flue above said tunnel, a fire box interposed in said flue intermediate its ends, and means communicating with said flue adjacent to its ends for withdrawing the heating media therefrom.

40 8. A leer comprising an elongate tunnel, means for moving articles of glassware there-through, a longitudinal heating flue above said tunnel, a fire box interposed in said flue intermediate its ends, means disposed at intervals along said flue for controlling the temperatures therein, and means communicating with said flue adjacent to its ends for withdrawing the heating media therefrom.

9. A leer comprising an elongate tunnel, 50 means for moving articles of glassware there-through, a longitudinal heating flue above said tunnel, a fire box interposed in said flue intermediate its ends, a cooling flue in prolongation of said heating flue, means disposed 55 at intervals along each of said flues for varying the temperatures therein, and suction means connected to each of said flues adjacent to its end for withdrawing the various media therefrom.

60 10. A leer comprising an elongate tunnel, means for moving articles of glassware there-through, a flue extending longitudinally beneath said tunnel through which heating media is adapted to be passed in a direction 65 parallel to the movement of the ware, a fire

box communicating therewith, a flue extending longitudinally above said tunnel, a fire box interposed therein intermediate its ends, whereby the portion of the upper flue toward the entrance end of said tunnel from the last mentioned fire box will conduct the media 70 in a direction counter-current to the direction of movement of the ware, and the remaining portion of said upper flue, in the direction of the movement of the ware, and means for withdrawing the heating media from each 75 of said flues adjacent to their ends distant from their respective fire boxes, each of said flues having a common wall with the bottom and top of the tunnel respectively. . 80

11. A leer comprising an elongate tunnel, means for moving articles of glassware there-through, a flue extending longitudinally beneath said tunnel, a fire box communicating therewith intermediate its ends, a flue extending longitudinally above said tunnel, a fire box interposed therein intermediate its 85 ends, whereby the portions of said flues toward the entrance end of said tunnel from said fire boxes will conduct the heating media 90 in directions counter-current to the ware, and the remaining portions of said flues, in the direction of movement of the ware, means disposed at intervals along portions of said flues for controlling the temperatures therein, and 95 means for withdrawing the media from said flues adjacent to their ends distant from their respective fire boxes. 100

12. A leer comprising an elongate tunnel, means for moving articles of glassware there-through, a flue extending longitudinally beneath said tunnel, a fire box communicating therewith intermediate its ends, a flue extending longitudinally above said tunnel, a fire box interposed therein intermediate its ends, 105 whereby the portions of said flues toward the entrance end of said tunnel from said fire boxes will conduct the heating media in directions counter-current to the ware, means disposed at intervals along portions of said flues 110 for controlling the temperatures therein, cooling flues arranged in prolongation of said heating flues to conduct air from the exit end of the leer toward the entrance end, and means for withdrawing the various media 115 from the ends of said heating flues adjacent to the entrance end of said tunnel and from the remaining flues adjacent to the meeting points of the cooling and heating flues. 120

13. A leer comprising an elongate tunnel, means for moving articles of glassware there-through, a longitudinal heating flue beneath said tunnel, a fire box communicating with said flue intermediate its ends, and draft impelling means outside said leer communicating directly with said flue adjacent to the ware-receiving end of said tunnel. 125

14. A leer comprising an elongate tunnel, means for moving articles of glassware there-through, a longitudinal heating flue beneath

said tunnel, a fire box communicating with said flue intermediate its ends, means disposed at intervals along said flue for controlling the temperatures therein, and draft impelling means outside said leer communicating directly with said flue adjacent to both ends thereof.

15. A leer comprising an elongate tunnel, means for moving articles of glassware therethrough, a longitudinal heating flue beneath said tunnel, a fire box communicating with said flue intermediate its ends, a longitudinally extending conduit communicating at one end with said flue adjacent to the ware receiving end of said leer, suction means communicating with the other end of said conduit, a longitudinal cooling flue above said tunnel, and a plurality of dampered passages extending between said cooling flue and said conduit.

20. 16. A leer comprising an elongate tunnel, means for moving articles of glassware therethrough, longitudinal heating flues respectively above and below said tunnel, a fire box 25 communicating with each of said flues intermediate its ends, the positions of said fire boxes being offset longitudinally of the tunnel, whereby the temperature curve along the tunnel rises to a maximum, has a substantially flat portion at said maximum, then falls.

30. 17. A leer comprising an elongate tunnel, means for moving articles of glassware therethrough, longitudinal heating flues respectively above and below said tunnel, and a fire box communicating with each of said flues, the fire box which communicates with the top flue being nearer the discharge end of said tunnel than the other of said fire boxes.

40. 18. A leer comprising an elongate tunnel, means for moving articles of glassware therethrough, longitudinal heating flues respectively above and below said tunnel, a fire box communicating with each of said flues 45 intermediate its ends, cooling flues in prolongation of said heating flues, the positions of said fire boxes being offset longitudinally of the tunnel, whereby the temperature curve along the tunnel rises to a maximum, has a substantially flat portion at said maximum, then falls, and dampered suction means communicating with each of said flues to withdraw the various media therefrom and regulate the temperatures therein.

55. 19. A leer comprising an elongate tunnel, means for moving articles of glassware therethrough, a muffle firebox substantially the same width as said tunnel and of substantial longitudinal extent associated with said tunnel, and a plurality of burners symmetrically disposed in said firebox, whereby to heat a substantial portion of said tunnel by conduction to a uniform high temperature and make a flat place in the temperature 60 curve along said tunnel.

20. A leer comprising an elongate tunnel, means for moving articles of glassware therethrough, and a muffle firebox substantially the same width as said tunnel and of substantial longitudinal extent, said fire box 70 having a common wall with the top of said tunnel, and a plurality of burners symmetrically disposed in said fire box, whereby to heat a substantial portion of said tunnel by conduction to a uniform high temperature. 75

21. A leer comprising an elongate inner tunnel, means for moving articles of glassware therethrough, a longitudinal heating flue associated with said tunnel, a fire box of substantial longitudinal extent communicating with said flue, said fire box having a common wall with said tunnel, and means for withdrawing the heating media from the end of said flue distant from said fire box. 80

22. A leer comprising an elongate inner 85 tunnel, means for moving articles of glassware therethrough, a longitudinal heating flue associated with said tunnel, a fire box of substantial longitudinal extent communicating with said flue, said fire box having a common wall with said tunnel, a plurality of dampered air inlet passages disposed at intervals along said flue, and means for withdrawing the heating media from the end of said flue nearer the discharge end of said 95 tunnel.

23. A leer comprising an elongate inner tunnel, means for moving articles of glassware therethrough, a longitudinal heating flue associated with said tunnel, a fire box 100 of substantial longitudinal extent interposed in said flue intermediate its ends, said fire box having a common wall with said tunnel, and means for withdrawing the heating media from points adjacent to the 105 ends of said flue.

24. A leer comprising an elongate inner tunnel, means for moving articles of glassware therethrough, a longitudinal heating flue associated with said tunnel, a fire box 110 of substantial longitudinal extent interposed in said flue intermediate its ends, said fire box and flue having a common wall with the roof of said tunnel, and means for withdrawing the heating media from points adjacent to the ends of said flue. 115

25. A leer comprising an elongate inner tunnel, means for moving articles of glassware therethrough, a longitudinal heating flue associated with one wall of said tunnel, 120 a fire box communicating with said flue, a plurality of temperature controlling means disposed at intervals along said flue, and a fire box of substantial longitudinal extent having a common wall with the opposite wall 125 of said tunnel, whereby to permit of differential heating of various portions of the ware during a portion of its travel through said tunnel.

26. A leer comprising an elongate inner 130

5 tunnel, means for moving articles of glassware therethrough, a longitudinal heating flue associated with the bottom of said tunnel, a fire box communicating with said flue, a longitudinal heating flue associated with the top of said tunnel, a fire box of substantial longitudinal extent interposed in the last named flue, the last mentioned fire box 10 having a common wall with the roof of said tunnel, and means connected with said flues adjacent to their ends for withdrawing the various media therefrom.

15 27. A leer comprising an elongate inner tunnel, means for moving articles of glassware therethrough, a longitudinal heating flue associated with the bottom of said tunnel, a fire box communicating with said flue intermediate its ends, a longitudinal heating flue associated with the top of said tunnel, a fire box of substantial longitudinal extent interposed in the last named flue, all said flues and the last mentioned fire box having common walls with said tunnel, and suction means 20 connected with said flues adjacent to their ends for withdrawing the various media therefrom.

25 28. A leer comprising an elongate inner tunnel, means for moving articles of glassware therethrough, a longitudinal heating flue associated with the bottom of said tunnel, a fire box communicating with said flue intermediate its ends, a longitudinal heating flue associated with the top of said tunnel, a fire box of substantial longitudinal extent interposed in the last named flue, means disposed 30 at intervals along said flues for varying the temperatures therein, the positions of said fire boxes being offset to provide a flat portion in the temperature curve of the leer, and suction means connected with said flues adjacent to their ends for withdrawing the various media therefrom.

35 29. A leer comprising an elongate tunnel, means for moving articles of glassware therethrough, flues associated respectively with the bottom and top of said tunnel, a fire box communicating with the bottom flue intermediate its ends, and a second fire box interposed in the top flue, said second fire box 40 being disposed further from the ware-receiving end of said tunnel than the first mentioned fire box, and said bottom flue extending to a point nearer the ware-discharging end of said tunnel than said top flue.

45 30. A leer comprising an elongate tunnel, means for moving articles of glassware therethrough, flues associated respectively with the bottom and top of said tunnel, a fire box communicating with the bottom flue intermediate its ends, a second fire box interposed in the top flue, means disposed at intervals along each flue for varying the temperature therein, said flues and said second fire box having common walls with said tunnel, 50 said second fire box being disposed further

from the ware-receiving ends of said tunnel than the first mentioned fire box, and said bottom flue extending to a point nearer the ware-discharging end of said tunnel than said top flue, and means for withdrawing the 55 various media from points adjacent to the cooler ends of said flues.

31. A leer for fusing a decoration adjacent to the tops of glass articles comprising an elongate tunnel, means for moving articles 60 of glassware therethrough, means for progressively and uniformly heating the articles to a point under the fusion point of the decorating material adjacent to the entrance end of the tunnel, means in the next succeeding portion of the tunnel for maintaining the tops of the articles at a uniform high temperature for a material time to fuse and bake on the decoration, means opposite said last named means for maintaining the bottoms of 65 the articles at a temperature low enough to prevent deformation, means in the next succeeding portion of the tunnel for again bringing the articles to a uniform temperature throughout to anneal them, and means for 70 cooling the articles at a predetermined rate.

32. A decorating leer comprising an elongate tunnel, means for moving articles of glassware therethrough, a muffle firebox substantially the same width as said tunnel and of substantial longitudinal extent associated with said tunnel, and a plurality of burners so disposed within said firebox as to provide a substantially even horizontal flame distribution therein, whereby to heat a substantial portion of said tunnel by conduction to a uniform high temperature and make a flat place in the temperature curve of said tunnel.

33. A decorating leer comprising an elongate tunnel, means for moving articles of glassware therethrough, a muffle firebox substantially the same width as said tunnel and of substantial longitudinal extent associated with said tunnel, and a source of hot gases so arranged as to distribute the gases substantially evenly over the horizontal area of said firebox, whereby to heat a substantial portion of said tunnel by conduction to a uniform high temperature and make a flat place in the temperature curve of said tunnel.

34. A decorating leer comprising an elongate tunnel, means for moving articles of glassware therethrough, a muffle firebox substantially the same width as said tunnel and of substantial longitudinal extent, said firebox having a common wall with the top of said tunnel, and a plurality of burners so disposed with respect to said firebox as to provide a substantially even flame distribution therein, whereby to heat a substantial portion of said tunnel by conduction to a uniform high temperature to mature the decoration on the ware therebeneath.

Signed this 20th day of December, 1927.

VERGIL MULHOLLAND.
